(57) **CLAIM**

The ornamental design for a collapsible portable bidet, as shown.

DESCRIPTION

FIG. 1 is a top perspective view of a collapsible portable bidet in an expanded state, showing my new design;
FIG. 2 is a bottom perspective view thereof;
FIG. 3 is a front side elevation view thereof;
FIG. 4 is a back side elevation view thereof;
FIG. 5 is a right side elevation view thereof;
FIG. 6 is a left side elevation view thereof;
FIG. 7 is a top plan view thereof; and,
FIG. 8 is a bottom plan view thereof.

The broken lines in the drawings depict portions of the form no part of the collapsible portable bidet that form no part of the claimed design.
